Patented Nov. 9, 1976

242,204

STRAW DISPENSER

Darrell D. Fish, Timonium, Md., assignor to Universal Synergetics, Inc., Pennsaukin, N.J.

Filed May 28, 1974, Ser. No. 473,405

Term of patent 14 years

Int. Cl. D7—06

U.S. CL. D7—75

Fig. 1

Fig. 2

Fig. 3

Fig. 4

FIG. 1 is a front perspective view of a straw dispenser showing my new design;

FIG. 2 is a top plan view thereof;

FIG. 3 is a front elevational view thereof;

FIG. 4 is an elevational view thereof of the side opposite that shown in FIG. 1.

The rear and bottom of the design are substantially flat and unornamented.

I claim:

The ornamental design for a straw dispenser, substantially as shown and described.
